UNITED STATES PATENT OFFICE

LAWRENCE D. REIMBOLT, OF CLEVELAND, OHIO, ASSIGNEE TO UNIVERSAL AUTOMOBILE FORWARDING COMPANY, A CORPORATION OF MICHIGAN

ORIFICE GOVERNOR

Application filed September 21, 1929. Serial No. 394,192.

This invention relates to internal combustion engines, and more particularly to means for governing the maximum amount of combustible mixture which may be drawn into the cylinders of an engine of this type.

One object of this invention is to provide a governor which has no moving parts, which may be readily fixed in position and effectively sealed, and which may be manufactured at a minimum cost.

A further object is to provide a governor of this type which may be attached to a standard manifold and carburetor assembly of an automobile engine without alteration thereto to limit the speed at which the car may be driven and prevent excessive racing of the engine when the car is in neutral, and which may be readily removed after it has served its purpose.

It has become customary to deliver new automobiles by driving them from the factory or assembly plant to their destination. It has frequently occurred, however, that the drivers employed for such delivery work have driven the cars at a higher rate of speed than is proper for a new car, resulting in burned out or loosened bearings, scored cylinders, or other injuries, which greatly lessen the life and value of the car. The governor which forms the subject-matter of this application is of such a nature that it may be attached to an automobile and sealed before the same is turned over to the driver, so that delivery of the automobile with the seal intact will be tangible evidence to the purchaser that it has not been abused.

In the drawings, which illustrate one embodiment of the invention;

Fig. 1 is a diagrammatic elevational view of the carburetor side of an internal combustion engine showing my improved governor in position between the companion flanges of the carburetor and the intake manifold;

Fig. 2 is a section taken on the line 2—2 of Fig. 1;

Fig. 3 is a section through the intake riser, taken on the plane indicated by the line 3—3 of Fig. 2;

Fig. 4 is a plan view of the governor detached from the engine; and

Fig. 5 is a section taken on the line 5—5 of Fig. 3.

Referring to the drawings wherein like symbols designate corresponding parts throughout the several views, the internal combustion engine 1 is provided with an intake manifold 2 and a carburetor 3 joined together by means of companion flanges 4 and 5 on a depending portion of the manifold and an upstanding portion of the carburetor, respectively. Oppositely disposed bolts 7, 7, passing through registering apertures in laterally extended portions of the flanges, normally secure the flanges together with a gasket 6 interposed therebetween.

My improved governor consists of a plate member 9 adapted to be clamped between the flanges 4 and 5 and having a rectangular portion 10 of a width to fit closely between the bolts 7, and two laterally extending arms 11 arranged to abut the bolts to position the plate. The plate is provided with a central aperture 8 positioned in such a manner as to be disposed in the intake passage and of such a size as to limit the flow of fuel to the intake manifold to a pre-determined quantity. The plate is provided with small apertures 12 near opposite edges thereof to receive a sealing wire 13, which is passed over both of the flanges 4 and 5 and fastened with a lead seal 14, as shown in Figure 5.

When it is desired to use the governor, the bolts 7 are loosened slightly and the rectangular portion 10 is placed between the flanges with the gasket on one side, and is pushed inwardly between the bolts 7 until the arms 11 contact with the bolts. The latter are then tightened down with sufficient force to effect a seal between the various parts. The plate is preferably made of relatively soft material, so that it will readily conform to the surface of the flanges and seal the joint. The wire 13 is then passed about the flanges and sealed by means of the lead seal 14. When the purchaser or dealer receives the car, the device may be quickly removed by cutting the wire, loosening the bolts, and slipping the plate from its position. The

original gasket 6 remains uninjured, and the car is restored to its original condition by simply tightening the bolts.

Although one embodiment of the invention has been described in detail, it is to be understood that the specific terminology employed is not intended to be restrictive, and that modification of the device disclosed can be made within the spirit and scope of the appended claims.

I claim:

1. In an internal combustion engine, a pair of fuel supply pipes joined together by means of mating flanges having bolts passing therethrough, and a governor consisting of an apertured plate arranged to be interposed between said flanges and to fit between and in contact with said bolts in such a manner as to be restrained from movement in two directions by the contact with said bolts, and to be freely removable in a third direction in the plane of said plate without removal of any bolts.

2. In an internal combustion engine, a pair of fuel supply pipes joined together by means of mating flanges having bolts passing therethrough, and a governor consisting of an apertured plate arranged to be interposed between said flanges and to fit between and in contact with said bolts in such a manner as to be restrained from movement in three directions by the contact with said bolts, and to be freely removable in a fourth direction in the plane of said plate without removal of any bolts.

3. In an internal combustion engine including a pair of fuel supply pipes having companion flanges at the meeting ends thereof, each of said flanges having a pair of oppositely disposed apertured extensions, and a pair of bolts passing through the corresponding apertures of said extensions, a governor for said engine comprising an apertured plate arranged so that, in assembling, it may be slipped between and in contact with said bolts, and between said flanges without removing any bolts.

4. In an internal combustion engine including a pair of fuel supply pipes having companion flanges at the meeting ends thereof, each of said flanges having a pair of oppositely disposed apertured extensions, and a pair of bolts passing through the corresponding apertures of said extensions, a governor for said engine comprising an apertured plate having lateral arms on two sides thereof, and arranged so that, in assembling, it may be slipped in between said flanges and between and in contact with said bolts, without removing any bolts, and may be positioned with said arms in contact with said bolts.

5. In an internal combustion engine including a pair of fuel supply pipes having companion flanges at the meeting ends thereof, each of said flanges having a pair of oppo-

sitely disposed apertured extensions, and a pair of bolts passing through the corresponding apertures of said extensions, a governor for said engine comprising an apertured plate arranged to be interposed between said flanges, said plate having a portion provided with parallel edges adapted, in assembling, to be slipped between and in contact with said bolts without removing any bolts and having a pair of oppositely extending wing portions having edges substantially perpendicular to said parallel edges adapted to contact with said bolts to position said plate.

6. In an internal combustion engine, a governor comprising a plate member adapted to be positioned between the companion flanges on the carburetor and intake manifold of such an engine, and having a rectangular portion adapted, in assembling, to be slipped between the bolts joining such flanges without removing any bolts, and a pair of oppositely extending wing portions adapted to contact with such bolts.

In testimony whereof I hereunto affix my signature this 14th day of September, 1929.

L. D. REIMBOLT.
